DESIGN FOR A BUFFING WHEEL PLATE OR SIMILAR ARTICLE

Samuel Goldberg, Detroit, Mich.

Application October 20, 1948, Serial No. 149,197

Term of patent 14 years

(Cl. D37—1)

To all whom it may concern:

Be it known that I, Samuel Goldberg, a citizen of the United States and a resident of the city of Detroit, in the county of Wayne and State of Michigan, have invented a new, original, and ornamental Design for a Buffing Wheel Plate or Similar Article, of which the following is a specification, reference being had to the accompanying drawing, forming a part thereof.

On the drawing:

Figure 1 is a front view of a buffing wheel plate or similar article showing my new design; and

Figure 2 is an end view of the plate.

I claim:

The ornamental design for a buffing wheel plate or similar article, substantially as shown.

SAMUEL GOLDBERG.
